UNITED STATES PATENT OFFICE

WILLOUGHBY M. McCORMICK, OF BALTIMORE, MARYLAND, ASSIGNOR TO McCORMICK & CO., INCORPORATED, OF BALTIMORE, MARYLAND, A CORPORATION OF MARYLAND

DESIGN FOR A BOTTLE

Application filed October 20, 1932. Serial No. 45,422. Term of patent 14 years.

To all whom it may concern:

Be it known that I, WILLOUGHBY M. McCORMICK, a citizen of the United States, residing at Baltimore, State of Maryland, have invented a new, original, and ornamental Design for a Bottle, of which the following is a specification, reference being had to the accompanying drawing, constituting a part thereof.

In the drawing:—

Fig. 1 is a front perspective view of the bottle showing my new design.

Fig. 2 is a rear perspective view thereof.

Fig. 3 is a top plan view thereof.

I claim:

The ornamental design for a bottle, substantially as shown.

In testimony whereof I have hereunto subscribed my name this 18th day of October, 1932.
